HEAT CONTROL REGULATOR AND ATTACHMENT DEVICE

Filed June 14, 1928

UNITED STATES PATENT OFFICE

SANFORD TAYLOR, OF GLENSIDE, PENNSYLVANIA, ASSIGNOR TO SAFEGARD ELECTRIC APPLIANCE COMPANY, OF PHILADELPHIA, PENNSYLVANIA, A CORPORATION OF PENNSYLVANIA

HEAT-CONTROL REGULATOR AND ATTACHMENT DEVICE

Application filed June 14, 1928. Serial No. 285,413.

My invention relates to a novel construction of a thermostatic heat control attachment device which is adapted to be attached to an electric percolator, flat iron, waffle iron, 5 or any other electrical heating appliances, whereby a novel heat control and regulation is readily and instantaneously attained by the rotation or adjustment of a rotatable disc positioned in substantially the longitudinal me- 10 dian line of the attachment housing in such a way that its periphery protrudes from the top and bottom thereof, so as to be readily manipulated, said disc having an eccentric groove provided with a locking recess cut in a 15 wall or face thereof and provided with indicia or graduations on its periphery graduated to the number of degrees Fahrenheit which the operator wishes the heating appliance to retain.

20 My invention further consists of a plurality of contact points, one of which is carried by the thermostatic element of novel construction and is juxtaposed to an upper contact point which is carried by a contact mem- 25 ber actuated by the eccentric groove of said rotary disc, said contact points being made from a non-magnetic and nonfusible material.

My invention further consists of a novel 30 construction of a sectional housing having a centrally disposed transverse recess in said housing members and a bearing in which is seated the hub of the rotatable disc having in its opposite wall an eccentric groove, and 35 a locking recess, said rotatable disc being axially revoluble on about the longitudinal median line of the housing, so that all the parts have a symmetrical, well balanced, and pleasing appearance, and said disc is readily manipulated by a thumb and finger of the operator.

To the above ends, my invention consists of a novel construction of a thermostatic heat control attachment device, composed of two 45 housing sections within which is contained and mounted the centrally disposed rotatable adjusting disc having indicia on its outer periphery, said disc being provided with an eccentric groove and a locking recess engaging 50 an offset member carrying a contact point,

which is juxtaposed in proximity to a contact point carried by the thermostatic element which is in electrical contact at all times with one of the contact clips.

My invention consists in providing a notch 55 or locking recess in said eccentric groove, registering with the "off" position of the rotary adjusting disc to guard against the accidental turning on of the current.

My invention further consists of novel 60 means engaging the knurled rim of said adjusting disc to prevent the backward turning or slipping of said disc, and to lock the latter in any position in which it is set, and in a novel manner of mounting the thermo- 65 static element and its adjuncts.

It further consists of other novel features of construction and advantage, all as will be hereinafter pointed out in the specification and claims appended hereto.

For the purpose of illustrating my invention I have shown in the accompanying drawings one form thereof which is at present preferred by me, since the same has been found in practice to give satisfactory and reliable 75 results, although it is to be understood that the various instrumentalities of which my invention consists can be variously arranged and organized and that my invention is not limited to the precise arrangement and organization of the instrumentalities as herein shown and described.

Figure 1 represents a perspective view of a thermostatic heat control attachment device embodying my invention.

Figure 2 represents a plan view of the bottom member of said device with the cover and internal structure removed.

Figure 3 represents a plan view of the top member of the device with the cover and internal structure removed.

Figure 4 represents a plan view of the bottom member of the device with cover removed and showing the internal structure.

Figure 8 represents a front view of Figure 7.

Figure 9 represents a perspective view of the conductor element shown detached.

5 Similar numerals of reference indicate corresponding parts in the figures. Referring to the drawings:—

1 designates my novel construction of a thermostatic heat control device, the same 10 comprising a cover or cap member 2, and the bottom or body portion 3, which constitute the housing, which is provided with a rotary disc 4 positioned at about the center of the longitudinal median line of said housing, its outer periphery being substantially 15 flush with the top and bottom bosses 5 and 6, as will be seen from Figures 1 and 5, whereby an enlarged chamber is formed within said bosses and a neat and finished appearance is given 20 to the device. The disc 4 is provided with the centrally disposed hub 7 which has its bearing in the recesses 8 formed in the corresponding portions of cap and bottom members 2 and 3, as will be understood from Figures 2 and 3. 25 On the face of the rotary disc 4 opposite the hub 7 is formed a groove 9 which is eccentric to said hub and to the axis of rotation of said disc, and in said groove 9 is positioned the lateral extension 10 of the curved spring arm 30 11, whose lower end is outwardly deflected as indicated at 12 and secured to the lower member 3 by one of the screws 13, as will be understood from Figure 6. The lateral extension 10 carries the contact 14 which is juxtaposed or in vertical alignment with the upper contact point 15 carried on the top 35 of the lower thermostatic element 16, which may be any thermostatic element sensitive to or affected by variations of temperature, said 40 thermostatic arm 16 being in contact with and secured to a lower complementary contact arm 17, by the screw 18 passing therethrough and threaded in the metallic eyelet 19 embedded in the lower housing member 3, as 45 will be best understood from Figures 4 and 5, said complementary contact arm 17 being suitably deflected to fit over the boss 20. The contact arm 17 is provided with the lateral integral extension 22, see Fig. 9, which is deflected as at 23 to fit over the boss 24 to which 50 it is secured by the screw 25 passing through the eye 26 and threaded into the lower housing member 3, as will be understood from Figures 4 and 9.

55 The upper and lower housing members 2 and 3 are provided with the rear openings 27^x for the admission of the electrical conductor 27, which openings merge into diverging grooves or channels 28 for the reception 60 of the bared ends (not shown) of said electrical conductor 27, to be fastened by the binding screws 13 which are threaded into the openings 30 in said lower member 3, one of said openings 30 being provided with the 65 metallic threaded eyelet 29.

31 designates registering channels in the upper and lower members 2 and 3 in which is adapted to seat the contact arm 32 which connects one of the bared ends of the electrical conductor 27 to the rear end of one 70 of the contact clips 34, which are secured by the screws 25 threaded in the corresponding opening 38 in the lower housing member 3.

33 designates a corresponding channel in the upper and lower housing members 2 and 75 3 in which seats the rear extension 12 of the spring arm 11 which is secured at its rear end by one of the binding screws 13 threaded in the metallic eyelet 29 in one of the holes 30 in the lower housing member 2. The contact 80 clips 34 seat in the corresponding registering recesses 36 extending between the bosses 24 and the upturned front edges 37 of the upper and lower housing members 2 and 3, said 85 clips 34 being secured by the screws 25 passing therethrough and threaded in the opening 38 in the lower housing member 3, as above set forth.

The thermostatic element 16 and the contact arm 17 seat within registering longitudinal recesses 40 in the upper and lower housing members 2 and 3, while the periphery of the disc 4 projects upwardly through the opening 50 in the upper housing member 2, and downwardly through the opening 41 in 95 the lower housing member 3. The upper and lower housing members 2 and 3 are secured together in their assembled position by the bolts 42 passing through the registering holes 43, as will be best understood from Figures 100 1,4 and 5.

The disc 4 is provided with the beveled edge 44, which is graduated or otherwise suitably marked to indicate the degree of heat, such as off, medium and high, and is 105 provided with the knurled or serrated edge 45 for turning or revolving said disc. To prevent the reverse turning of the disc 4, I provide an arm 46 which is superimposed upon the rear portion 12 of the spring arm 11 110 in the channel 33, and the rear end of which is secured by the binding screw 13 (see Fig. 4), the front end of said arm 46 being deflected to form a pawl 46^x to engage the roughened edge 45 of the disc 4, thus preventing the turning of said disc in reverse direction.

The groove 9 in the disc 4 is provided with the locking notch or recess 47, which engages the lateral extension 10 of the spring arm 11, 120 said notch 47 being in registering alignment with the "off" position of the device, thereby preventing the accidental turning on of the current, which might be the case if the disc 4 were free to revolve so that the notch 47 125 serves to lock the rotary disc 4 in the "off" position.

The operation is as follows:—

When the disc 4 is in the "off" position, 130 and the lateral extension 10 of the spring

arm 11 is locked in the notch 47 of the groove 9 in said disc, the circuit is broken and no heat is developed. When the disc 4 is rotated toward the position marked "Medium" contact is established between the contact points 14 and 15, and the circuit is completed. When the device being heated, such as an electric iron, has developed a certain degree of heat corresponding to the degree designated "medium" the thermostatic arm 16 is deflect- ed downwardly by the heat generated by electric current and the circuit is broken by the separation of the contact points 14 and 15. When the device has cooled off or fallen to the degree of temperature less than that indicated "medium" the thermostatic arm 16 assumes its normal upper position and contact is again established. When the device is set to "hot", it takes a greater degree of heat to deflect the thermostatic arm 16 suffi- ciently to break the circuit, since due to the eccentricity of the groove 9, the upper contact point 14 is pressed down a greater dis- tance toward the contact point 15 when the device is set to "hot" than it is when the device is set to "medium", and therefore re- quires a greater amount of deflection of the thermostatic arm 16 to break the circuit.

The contact clips may be constructed so as to receive square or round pilots, and are in- terchangeable. The plug sections or housing are preferably made of brown bakelite, and the adjusting disc 4 of red bakelite.

My novel device which can be attached to electric flat irons or any other heating appliance using alternating current controls the heat by adjusting the revolving disc 4, whose periphery protrudes beyond the sides of the plug housing and as stated is graduated to the number of degrees Fahrenheit the operator wishes the heating appliance to retain.

My novel device is interchangeable since it can be put on the appliance either side up and can be detached instantly and comfortably by reason of the circular ratchet knurls on the sides of the housing, which enables the operator firmly to grasp or grip the device to detach it from the appliance.

It will be further apparent that when the housing sections seen in Figs. 2 and 3 are as- sembled as seen in Figs. 1 and 5, there is an enlarged heat chamber formed within the recesses 40 and the channels 36 whereby the action of the thermostatic element is ren- dered more sensitive and positive.

I am aware that the invention may be em- bodied in other specific forms without depart- ing from the spirit or essential attributes thereof, and I therefore desire the present embodiment to be considered in all respects as illustrative and not restrictive, reference be- ing had to the appended claims rather than to the foregoing description to indicate the scope of the invention.

Having thus described my invention what

I claim as new and desire to secure by Letters Patent, is:-

1. A thermostatic device of the character stated, comprising a housing, contact clips therein, an auxiliary conducting member comprising a longitudinal body portion, and a deflected portion electrically connected to the rear of one of said contact clips, a thermo- static arm having one end thereof in contact with said auxiliary contact member and the free end thereof provided with an upper con- tact point, a rotatable disc mounted in said housing and having an eccentric groove there- in provided with a locking recess, a spring arm carrying a contact, and an extension on the free end of said spring arm engaging said groove whereby, said spring arm contact point may be raised and lowered and locked by the rotation of said disc.

2. A thermostatic device of the character stated, comprising a housing, contact clips therein, an auxiliary conducting member centrally disposed between said clips and having electrical contact with one of said clips, the other of said clips being connected to a source of electrical energy, a thermostatic arm having one end thereof connected with said auxiliary contact member and having its free end provided with an upper contact point, a ro- tatable disc having an eccentric groove there- in, a spring arm carrying a contact, an exten- sion on the end of said spring arm engaging said groove, whereby said spring arm con- tact point may be raised and lowered, and a pawl for locking said disc from reverse ro- tation.

3. A thermostatic device of the character stated, comprising a housing, contact clips therein, an auxiliary conducting member centrally disposed between said clips and elec- trically connected to one of said clips, the other of said clips being connected to a source of electrical energy, a thermostatic member having one end thereof connected with said auxiliary contact member and having its free end provided with an upper contact point, a ro- tatable disc having an eccentric groove and a locking recess therein, a spring arm having one end thereof connected to a source of elec- trical energy and the free end thereof pro- vided with a bottom contact point juxtaposed to the contact point on the free end of said thermostatic member, an extension on said spring arm adapted to engage said eccentric groove and locking recess, whereby the con- tact point on said spring arm may be raised, lowered, and locked with respect to the con- tact point on said spring arm, and means for locking said disc from rotation in a reverse direction.

4. A thermostatic device of the character stated, comprising a housing, contact clips therein, an auxiliary conducting member hav- ing electrical connection with one of said con- tact clips, a thermostatic arm having one end

thereof in contact with said auxiliary conducting member and the free end thereof provided with a contact point, a rotatable disc having "off", "medium" and "hot" indicia thereon mounted in said housing and having an eccentric groove therein, a spring carrying a contact, and an extension on the free end of said spring arm engaging said groove, whereby said contact point may be raised and lowered by rotation of said disc, said groove having a locking recess therein, in which an extension of said contact point is adapted to seat when in its uppermost raised position, said locking recess coinciding with the "off" indicia of said disc.

5. A thermostatic device of the character stated, comprising a housing, contact clips therein, an auxiliary conductor having electrical connection with one of said clips, a 20 thermostatic member having one end thereof in contact with said auxiliary conductor member and the free end thereof provided with an upper contact point, a rotatable disc mounted in and projecting through said housing and having an eccentric groove with 25 a locking recess therein, a spring arm having a contact thereon, an extension on the free end of said spring arm engaging said eccentric groove and locking recess, whereby said 30 spring arm contact point may be raised and lowered by the rotation of said disc, said disc being provided with a rear, graduated peripheral portion containing "off", "medium" and "hot" indicia, said locking recess coinciding 35 with said "off" indicia, and a locking pawl engaging the periphery of said disc for determining the position of said spring arm contact point.

SANFORD TAYLOR.
